United States Patent Office.

EDWIN F. HUTCHINSON, OF AUBURN, MAINE.

Letters Patent No. 77,044, dated April 21, 1868.

IMPROVEMENT IN LAND-ROLLER.

The Schedule referred to in these Letters Patent and making part of the same.

TO ALL WHOM IT MAY CONCERN:

Be it known that I, EDWIN F. HUTCHINSON, of Auburn, in the county of Androscoggin, and in the State of Maine, have invented new and useful Improvements in Land-Rollers; and I do hereby declare that the following is a full, clear, and exact description thereof, reference being had to the accompanying drawings, and to the letters of reference marked thereon, making a part of this specification.

Figure 1 represents a view of the roller with broken lines at the end, showing a section of the head B.

Figure 2 represents an end view of the roller.

In the annexed drawings, A represents a cylinder, of suitable size, which may be of wood or other material. At each end of this cylinder is a cast-iron head, B. This head is a circular disk, having an outer projecting flange around the entire circumference, and is provided with a suitable journal, d, in its centre. One of these heads is placed at each end of the cylinder A, and a series of metal staves, C C, is secured over the cylinder, and connected to the heads B B by means of bolts and nuts x x, as seen.

In some cases I may dispense with the cylinder A, and connect the staves C C to the heads B B alone. By means of these heads B B, a roller can be easily made, and of any size or material. The roller is connected to any frame by means of its journals d d, and suitable bearings therefor on the frame.

It will be seen that the heads B B are solid plates, with flanges and journals on their exteriors, as described, and prevent the ingress of clods of dirt, or stones or other substances when the roller is in operation. By means of these plates, as constructed, I can regulate the weight of the roller to suit the earth that is being rolled; for instance, I may use the roller without any filling at all, or I can extract one of the heads from the staves, and place a filling, A, or a partial filling, when desired.

I am aware that a roller constructed of a series of staves, and connected by bolts to a metal band or wheel at each end, is not new.

What I claim, and desire to secure by Letters Patent, is—

The metallic heads B B, consisting of solid metallic plates, with exterior flanges and journals, as specified, and used in combination with staves C, connected by the bolts x, in the manner as set forth.

In testimony that I claim the foregoing, I have hereunto set my hand, this 16th day of January, 1868.

EDWIN F. HUTCHINSON.
